CLAIM

The ornamental design for an integrated pusher for beverages, as shown and described.

DESCRIPTION

FIG. 1 is a top perspective view of an integrated pusher for beverages showing my new design;

FIG. 2 is a bottom perspective view thereof;

FIG. 3 is a front elevational view thereof;

FIG. 4 is a rear perspective view thereof;

FIG. 5 is a left side view thereof;

FIG. 6 is a right side view thereof;

FIG. 7 is a bottom plan view thereof;

FIG. 8 is a top plan view thereof;

FIG. 9 is an exploded view thereof;

FIG. 10 is another exploded view thereof, shown in an alternate position; and,

FIG. 11 is an enlarged view of portion 11 in FIG. 10.

The dash-dash broken lines in the drawings depict the portions of the integrated pusher for beverages that form no part of the claimed design.

The dot-dash broken lines in the drawings depict the boundaries of the partial enlarged views that form no part of the claimed design.

1 Claim, 8 Drawing Sheets
